UNITED STATES PATENT OFFICE.

ALEXANDER K. SCHAAP, OF NEW YORK, N. Y.

PISTON-RING.

1,381,668.

Specification of Letters Patent. Patented June 14, 1921.

Application filed April 3, 1920. Serial No. 371,016.

To all whom it may concern:

Be it known that I, ALEXANDER K. SCHAAP, a citizen of the United States, and a resident of the city of New York, county 5 of Kings, and State of New York, have invented a new and useful Improvement in Piston-Rings, of which the following is a specification.

The object of my invention is to provide 10 a one piece piston ring which will always fit with a tight joint and never bind or break. This is accomplished by taking two cuts on each side of the ring, each cut going half way through in such a manner that the exterior 15 peripheral edges come together before the interior peripheral edges so that when the ring is compressed, the interior edges never met, and therefore, to make these cuts so that one extends in a diagonal 20 direction with regard to the other. This object is accomplished by my invention, one embodiment of which is hereinafter more particularly set forth.

For a more particular description of my 25 invention, reference is to be had to the accompanying drawing, forming a part hereof, in which—

Figure 1 is a plan view of my improved 30 ring.

Fig. 2 is an enlarged plan view of one side 35 of the joint of the same.

Fig. 3 is an inverted plan view of the 40 same joint that is shown in Fig. 2.

Fig. 4 is a side elevation of the joint, and 45 Figs. 5 and 6 show opposite ends of the ring, one end being at each side of the joint.

Throughout the various views of the drawing, similar reference characters designate 50 similar parts.

My improved ring 1 is generally made 55 with substantially four cuts which will be designated by the edge walls which remain after the cut is taken. The first edge is designated 2 and for the want of a better term may be called a short cut, because it is not as long as the opposing cut 3 which is opposite the same. It will be noted that the outer ends of the edges 2 and 3 more nearly 60 approach each other than the inner and that it is apparent from Fig. 4 that each of these cuts extends substantially half the thickness of the ring 1. After the cuts are made which produce the edges 2 and 3, the ring is turned over and two more cuts 4 and

5 are made exactly the same as before; that 55 is the long cut is 5 and overhangs the short cut 4 and it will be further noticed that the four cuts have one intersecting quadrilateral 7 in common which is open. As this quadrilateral is well within the groove of 60 the piston ring when the ring is in use, its presence is immaterial.

It will be noted that the cuts 2, 3, 4 and 5 form ends which interlock so that one cannot ride in on another to any great extent 65 and when the ring is in use in a piston, the irregularities of the cylinder will cause the piston ring to expand and contract as the piston rises and falls. This expansion and contraction of the ring causes the opposing 70 cuts 2 and 3 on the one cylinder and 4 and 5 on the other to approach and recede as they approach by capillary action. The excess liquid is forced to the interior of the ring because the exterior ends are closer together 75 than the interior so that this ring in the piston acts as a capillary pump to draw oil from the entire exterior periphery of the ring and force the same in the groove of the piston and back of the piston ring 80 so that there is always a gentle hydraulic pressure of the ring against the cylinder wall which is equally radial and applied along the entire periphery so that as the ring wears in the cylinder it wears the cylinder true and in round and not out of round. Furthermore, when an explosion takes place 85 above the piston and drives the same, the piston drives the ring in the cylinder so that the ring is against the upper wall of the 90 groove and slightly away from the lower wall of the groove and at that time, if there is any excess oil at the interior of the ring, it has a chance to escape equally all around the interior wall of the cylinder and while 95 so escaping it thoroughly lubricates the cylinder just ahead of the power stroke of the engine. This is the time when perfect lubrication is required most and it is at the very time which the ring causes the lubrication 100

This ring may be applied in any suitable engine but is designed for an ordinary piston of an internal combustion engine where the cylinder is lubricated by the splash of 105 the crank in the crank case.

While I have shown and described one embodiment of my invention, it is obvious that

it is not restricted thereto, but is broad enough to cover all structures that come within the scope of the annexed claim.

Having thus described my invention, what

5 I claim is:

A single piece piston ring having an overlapping joint and provided with two edges one overhanging the other and longer than the other, at each side of the ring, the said

edges being so arranged and disposed that 10 one part runs across the other part, and these edges have a quadrilateral in common and adjacent edges on opposite ends approach each other more closely at the exterior periphery of the ring than at the interior periphery. 15

ALEXANDER K. SCHAAP.
